UNITED STATES PATENT OFFICE

PATRICK J. MCINTYRE, OF DETROIT, MICHIGAN, ASSIGNOR TO WOLVERINE TUBE COMPANY, OF DETROIT, MICHIGAN, A CORPORATION OF MICHIGAN

HEAT-EXCHANGE APPARATUS

Application filed March 19, 1928. Serial No. 262,921.

This invention relates to heat exchange apparatus and more particularly to an improved and simplified form of cooling or condenser coil.

From the nature of the herein described apparatus it will be readily apparent that this apparatus is capable of many and varied uses. However, it finds particular utility when used as a condenser in mechanical refrigerating apparatus, as a radiator for steam or hot water heating, or as a cooling radiator.

One of the objects of this invention is to provide an improved construction of coil formed from one piece which is bent to provide a plurality or series of straight parallel pipes or sections of flat tubular cross section connected by circular or round tubular sections at the ends thereof. With such a construction the flat tubes constituting the fin receiving portions of the coil afford a greater radiating surface and provide an efficient means for associating the fins therewith. By providing a coil, the bent portions of which are of circular cross section, in combination with the flat coil sections, back pressure in the coil is eliminated or minimized by permitting a freedom of flow therethrough.

Another object of the invention is to provide a construction of this character wherein each tube of the coil is provided with separate fins and cooled independently of the remaining tubes.

Still another object of this invention is to provide a construction of the herein described character which may be quickly and economically manufactured, assembled with facility and which will enjoy a maximum efficiency.

The several objects, advantages and the novel details of construction of one embodiment of this invention will be made more apparent as this description proceeds, especially when considered in connection with the accompanying drawings, wherein:

Figure 1 is a fragmentary elevational view of a coil constructed in accordance with this invention.

Figure 2 is a fragmentary vertical sec-

tional view taken substantially on the plane indicated by line 2-2 in Figure 1.

Figure 3 is a fragmentary longitudinal sectional view taken substantially on the plane indicated by line 3-3 in Figure 2. 55

Figure 4 is a fragmentary perspective view of a section of the coil.

Figure 5 is a detail sectional view taken substantially on the plane indicated by line 5-5 in Figure 1, and 60

Figure 6 is a fragmentary elevational view of a length of tubing before the same is bent to form the coil.

Referring now particularly to the drawings wherein like reference characters indicate like parts it will be noted that there is illustrated a cooling coil constructed from a single length of tubing bent to form a plurality of straight parallel tube sections 10 arranged in spaced relation in the same 70 general plane. The straight parallel tube sections 10 are connected at the ends by curved or bent portions 11. Obviously by constructing the coil from a single length of tubing the necessity for joints, fittings or 75 other connections therein is eliminated.

By reference to Figure 6 it will be noted that the coil is bent from a length of tubing 12 which has certain portions 13 thereof throughout its length flattened while the 80 portions 14 intermediate the flattened portions are left circular in cross section. The length of tubing which is to be bent to form the coil may be conveniently and economically prepared in this manner by taking a 85 piece of tubing circular or round in cross section and flattening the tube at spaced points throughout its length. In the completed coil the flattened portions 13 form the straight parallel tubes 10 and the portions 90 14 which are circular in cross section form the bends or curved portions 11.

Numerous advantages are obtained from such a construction. In the first place by forming the straight portions 10 of a flat 95 tubular construction the radiating surfaces thereof are increased. In the second place, the fin plates or members, yet to be referred to, may be more conveniently associated therewith. In the third place, curved por- 100

tions 11 of round cross section permit the contents of the coil to pass freely therethrough and prevent or eliminate to a large degree back pressure which might develop in the coil. This back pressure results principally from the fact that the contents of the tube when flowing from one straight portion 10 to the next adjacent straight portion must reverse its direction of flow and if a tube of flat cross section throughout its length were bent to produce a coil of the herein described character the flow of the contents of the tube would be so restricted at the curved portions thereof as to produce considerable back pressure and thus reduce the efficiency of the device. In accordance with the present invention the same advantages are obtained as though a plurality of straight tubes were employed connected at the ends by U-shaped fittings, these advantages being realized with a construction which may be much more readily and economically manufactured.

Associated with each of the straight tube portions 10 of the coil is a pair of fin members 15. Each fin member may be conveniently developed from a flat sheet of metal which is bent to form a plurality of oppositely extending alternately arranged return-bent portions 16 and 17 respectively, the crests of these return bent portions being arranged parallel or in the same plane. The crest of each return bent portion 17 is formed with a depression 18 substantially corresponding in shape to one half of the cross sectional shape of the flat tube portions 10. A pair of fin members 15 are associated with each of the tubes 10 and the combined depressions 18 of each pair of fin members form recesses or passages extending longitudinally or lengthwise of the fin members for accommodating the flat portions 10.

In assembling the fin members with the coil, solder is placed between those portions of the fin members which engage the tube and also those portions of the fin members which engage one another. With the parts secured in this position the whole structure is subjected to a temperature sufficiently to melt the solder and when the assembled structure is later removed and the solder permitted to harden the fin members are rigidly secured to the tubes and to one another, an efficient heat transferring union between the several members being provided. A layer of solder between the fin members 16 and the tube 10 is indicated by the reference character 19 and the line of solder between the engaging faces of the fin members is indicated by the reference character 20.

Obviously the coils may be formed of any length or size and a heat exchange unit may comprise one coil or a number of coils asso-

ciated with one another side by side in spaced parallel relation or in any desired or preferred manner. It is noted that a pair of fin members 15 is associated with each of the tubes 10, by this construction the mounting of the fin members upon the tubes is facilitated and the effective heat radiating surface of the coil is increased.

While an embodiment of this invention has been described and illustrated herein somewhat in detail it will be readily apparent to those skilled in this art that various changes may be resorted to without departing from the spirit and scope of this invention and to this end reservation is made to make such changes as may come within the purview of the accompanying claims.

What I claim as my invention is:—

1. In heat exchange apparatus, a single length of tubing bent to provide a plurality of spaced straight parallel tubes and curved portions connecting the same, the straight tubes being of flattened cross section and the curved portions being of circular cross section.

2. In heat exchange apparatus of the class described, a single length of tubing bent to form a plurality of straight spaced parallel tube sections and a pair of fin members associated with each tube section, the pair of fin members associated with each tube section being independent of the fin members associated with the other tube sections and each fin member comprising a strip bent to form a plurality of oppositely extending alternately arranged return-bent portions, the opposed crests of the return-bent portions of said fin members being recessed for embracing engagement with said tube section and being secured to the corresponding portion of the other fin member of the same pair.

3. In the method of forming heat exchange coils, those steps which consist in deforming a length of tubing, at points throughout its length, to provide portions of flat tubular cross section and bending said length of tubing at the non-deformed portions to provide a plurality of straight tube sections.

4. In the method of forming heat exchange apparatus, those steps which consist in deforming a length of tubing which is circular in cross section at spaced points throughout its length to produce portions of flat tubular cross section and bending the tubes at the non-deformed portions thereof to provide a plurality of straight spaced parallel portions.

5. In the method of forming heat exchange apparatus, those steps which consist in deforming a length of tubing which is circular in cross section at spaced points throughout its length to produce portions of flat tubular cross section and bending the tubes at the nondeformed portions thereof to provide a plurality of straight spaced parallel portions,

and assembling fin members with the straight parallel portions.

6. In a heat exchange apparatus, the combination of a plurality of spaced straight tube sections, each tube section being of flattened cross sectional shape and being connected to the next adjacent straight tube section, and an independent set of fin members associated with each straight tube section.

7. The method of forming a heat exchange apparatus which consists in forming an elongated tube substantially circular in cross section, deforming sections of the said tube at spaced points throughout its length to vary the cross sectional shape thereof, and bending the said tube at the junctures of the non-deformed sections of the tube with the deformed sections thereof to form a series of parallel portions of deformed cross sectional shape and a plurality of connecting portions of non-deformed cross sectional shape.

In testimony whereof I affix my signature.
PATRICK J. McINTYRE.
